UNITED STATES PATENT OFFICE.

HENRY H. DYER, OF SOMERVILLE, MASSACHUSETTS...

POCKET-FILTER.

1,000,332.

Specification of Letters Patent.

Patented Aug. 8, 1911.

Application filed November 11, 1910. Serial No. 591,886.

To all whom it may concern:

Be it known that I, HENRY H. DYER, a citizen of the United States, residing at Somerville, in the county of Suffolk and State of Massachusetts, have invented certain new and useful Improvements in Pocket-Filters, of which the following is a specification.

This invention is designed primarily to construct a filter which may be carried in the pocket of the user, and thus be an article which will be desired by travelers, hunters, men, etc.

This device is constructed so that it may be easily taken apart or assembled, and is provided with a telescoping section which is inserted in the mouth of the user for drawing the liquid through the filter and thence into the mouth.

20 Due to the construction of this pocket filter, the same can be carried in the same manner as a pencil or pen, and so will not be in the way but will be a very useful and desirable article.

25 With the above and other objects in view, this invention consists in the construction, combination, and arrangement of parts, all as hereinafter more fully described, claimed, and illustrated in the accompanying drawings, wherein—

Figure 1 is a perspective view of the present invention illustrating the same as it will be carried in the pocket; Fig. 2 is a longitudinal section disclosing the construction 35 of the pocket filter; Fig. 3 is an elevation of the telescoping section which is secured to the filter; Fig. 4 is a detailed view used in the construction of the filter; Fig. 5 is a sectional view taken along line 5—5 of 40 Fig. 3.

Referring more particularly to the drawings, 1 indicates the body of the filter which may be of any desired shape. The body 1, as illustrated, comprises a tubular casing 2 provided with external screw threads on one terminal thereof, and internal screw threads on the opposite terminal, said external screw threads being adapted to receive a cap 3 containing a perforated plate or other foraminous member and constituting the base or outer terminal of the filter which is to be inserted in the liquid. The opposite terminal of the tubular member 2 is provided with a seat 4 to receive a perforated 55 disk or other foraminous member 5, the

space between said disk and the cap 3 being filled with any desired filtering material 6, as will be clearly understood from the drawing. The internal screw threads above referred to are adapted to receive the external screw threads provided on one terminal of the section 7 which, together with a pipe or section 8 of smaller diameter adapted to telescope in the section 7, form a telescopic member through which the water is drawn and conveyed to the mouth. This pipe or section, as secured to the casing or tubular member 2, is adapted to bear against the member 5, and thus retain the same from displacement. The opposite terminal of the section 7 is provided with internal screw threads which engage the external screw threads of the mouth piece or conical member 9, the latter being provided with a central bore or opening in which the section 8 is adapted to reciprocate. The pipe or section 8 is provided with an enlarged head 10 on its inner terminal to limit the outward movement of the same. A cap 11 is provided and adapted to fit over the tubular member 9 and engage the section by friction to prevent any foreign substance from entering the tubular member or pipe 8 when the article is not in use. Adjacent to the terminal of the pipe 7 which is secured to the filter is provided a slot 12 which is adapted to receive a similarly shaped perforated plate 13, as illustrated in Fig. 5. This slot 12 is so located as to be concealed when the telescopic member is secured to the filter body, and thereby accidental displacement or loss of the plate 13 is prevented. This perforated plate or other foraminous member tends to refilter any foreign matter which may have escaped the filter body.

If it is desired, the section 8 may be dispensed with by telescoping it in the outer section 7 and using the conical member 9 as a mouth piece, but if it is inconvenient to use the pocket filter in this way, the latter 100 may be lengthened by drawing out the tube 8, as illustrated in Fig. 2, using the outer terminal of said tube as a mouth piece. If it is ever necessary, a rubber tubing may be attached to the tube 8, which will readily be 105 understood.

Having thus fully described my invention, what is claimed as new is:—

A pocket filter comprising a tubular body, and foraminous cap members carried there-

3, filtering material interposed between said cap members, a telescopic member secured to said tubular body and adapted to prevent displacement of one of said caps, ie section of said telescopic member being provided with a slot adjacent to one terminal thereof, and a foraminous member adapted to be received by said slot, said

member being prevented from displacement by said tubular body as set forth.

In testimony whereof I affix my signature in presence of two witnesses.

HENRY H. DYER.
